UNITED STATES PATENT OFFICE.

CHARLES I. CHAMBERS, OF SEATTLE, WASHINGTON.

PUMP.

Application filed March 6, 1926. Serial No. 92,766.

The invention relates to an improvement in pumps of the submerged type and operating under fluid pressure.

The principal object of the invention is to prevent wastage of power by preventing the admission of the air under pressure to the pump until the water or other fluid has accumulated therein to a certain extent, thus preventing attempted operation of the pump in the absence of sufficient water or other fluid therein for pumping purposes.

A further object is the utilization of the water level within the pump proper as a means for limiting the pumping or ejecting operation of a particular cycle, whereby a maximum discharge is insured in all operations.

The invention is illustrated in the accompanying drawings, in which:

Fig. 1 is a plan view of the improved pump.

Fig. 2 is a section of a portion of the pump taken on the line 2—2 of Fig. 1.

Fig. 3 is a vertical section of the pump taken on the line 3—3 of Fig. 1, the parts being shown in normal positions, that is, the positions assumed while water or other fluid is accumulating in the pump cylinder.

Fig. 4 is a view similar to Fig. 3, with the parts in pumping position.

The improved pump is made up of two main parts, a cylinder 1 and a valve section 2. The cylinder 1 comprises a cylindrical body of appropriate length in diameter having an inlet 3 in the bottom, controlled by a gravity valve 4, slidably mounted upon a stem 5 and limited in movement by the head 6 of the stem. Thus when submerged, and in the absence of pressure within the cylinder, the valve 4 opens to freely admit the surrounding liquid to the interior of the cylinder.

The valve section 2, which is in the form of a casting, has a base 7, which is removably secured in a fluid tight manner to the upper end of the cylinder 1 by threaded bolts 8. This casting is interiorly formed immediately above the base and to one side of the center thereof with an air exhaust or discharge passage 10, which communicates with the interior of the cylinder through a port 9 formed in the base. That portion of the base surrounding the port 9 on the cylinder side of the base is formed to provide a valve seat 11, and a valve 12 is arranged to close this port from the cylinder side.

The valve 12 is provided with a stem 13 which extends upwardly in the casting and seats loosely in a sleeve 14 depending from an enlarged head plate 15 and guided in a projection 16 rising from the upper wall 17 of the discharge passage 10, a spring 18 surrounding the guide 16 and bearing between the wall 17 and the head 15, and normally holding the plate 15 at its upper limit of movement. The plate 15 overlies the upper wall of the casting proper, which throughout the area of the plate is formed to present a concave depression 19, and the plate 20 is secured to the casting overlying and closing this depression to form a pressure chamber 21. Between the plate 20 and the corresponding edge of the concave depression 19, there is arranged a flexible diaphragm 22 which overlies and at all times bears on the valve plate 15.

The valve section 2 beyond the plate 20 is formed for the reception or connection of the service pipes, such as a water discharge pipe 23, which extends through the valve section and into the cylinder 1, terminating above the lower end of the cylinder; an air discharge or exhaust pipe 24 which extends into the valve casing and is in open communication with the exhaust passage 10; and an air pressure pipe 25 leading from any suitable source of air under pressure to and within the valve section below the exhaust passage 10.

The air pressure pipe 25 opens into a valve chamber 26 in the base 7 of the valve section, communicating with such chamber through a plurality of openings 27 formed in a bushing 28 for the chamber. A sliding valve 29 having an annular channel 30 is slidably in the bushing, and obviously when in line with the openings 27, will cut off communication between the air pressure pipe and the cylinder 1, while when the valve is raised above the openings 26, the air under pressure from the pipe 25 may freely enter the cylinder. The outlet from the valve chamber 26 to the cylinder 1, is normally closed by a plate 31, and a pipe 32 extends through the plate to establish communication between the valve chamber and cylinder, the specific function of this pipe being later described.

The valve section 2 is formed near one edge with a passage 33 which extends through the base 7 and to the cylinder 1, the opposite end of the passage leading through the edge

of the concave depression 19 and through a registering passage 34 in the plate 20, opening through the bottom of said plate above the diaphragm 22. Pressure admitted through this passage 33 therefore will act on the diaphragm to depress the valve plate 15 and thereby open the valve 12, under certain conditions to be explained.

The valves 12 and 29 are provided with extensions 35 and 36 respectively, which are connected to a lever 37 pivoted at one end at 38 to an extension 39 depending from the base 7 of the valve section 2. To the lower side of the lever 37 is secured a pan 40 of appreciable depth, fully open at the bottom, but otherwise closed. The pipe 32, forming an extension of the pressure inlet, leads to and opens within the pan 40. In the lower portion of the cylinder 1 is arranged a valve operator in the form of a pan-like vessel 41 open at the top and otherwise closed, supported for pivotal movement at 42 relative to a fixture 43 projecting from the cylinder, and counterbalanced by a weight 44. The balance pan 41 is connected by a rod 45 to a lever 46 pivotally supported on the lower side of the base 7 of the valve section 2 and provided at an appropriate point with a valve disc 47 adapted to control the passage 33.

The chamber above the diaphragm 22 has a normally open bleed passage 48 leading to the air exhaust pipe 24, balance bleed openings 49 being formed between the chamber 21 and the exhaust passage and between the interior of the sleeve 14 and the chamber 21.

Normally, the valve 29 will be in position to cut off air pressure admission to the cylinder and the valve 12 will be in open position to establish communication between the air exhaust and the cylinder, the position of these valves being incident to the gravitational movement of the lever 37. Assuming the pump submerged in the water to be pumped, valve 4 opens and water fills the cylinder until closing the open end of the pan 40. Under the pressure on the air trapped in this pan, the further accumulation of water moves the pan upwardly, closing the valve 12 and opening the valve 29. Air under pressure is admitted to the surface of the

water within the cylinder, acting in the usual way to force said water through the discharge pipe 23. As the level of the water falls incident to this discharge, the level recedes below the pan 41, which being open at the top is left filled with water. This over-balances the weight 44, opens the valve 47, permits the pressure to enter above the valve diaphragm and by reason of the greater area of the valve plate 15, to depress and open the valve 12. This movement of course depresses the lever 37 and cuts off the admission of air pressure by closing the valve 29. Free escape of the pressure is thus permitted, and on a balance being reached, water again flows into the cylinder 1, restoring the balance pan to normal position, closing the valve 47, and the cycle of operations described is repeated.

It is to be noted that the apparatus as a whole is particularly economical as to the use of power. Under ordinary conditions, the action of the pan 40 under the incoming water would be slow, and hence there would be some wastage of power of the incoming air. As such air pressure however, is delivered to the interior of the pan above the level of the water therein, or at least substantially at the level of the water therein, the effect of this air is to cause an unusually quick movement of the pan 40, the rapid closing of the valve 12, and the consequent loss, of little, if any, of the pressure. Of course, it is understood that the pressure being initially delivered in the sealed pan 40 will tend to insure closing of the valve 12 before such air percolates through the water to the surface thereof around the pan.

What is claimed as new, is:—

A pressure pump of the submerged type, including a cylinder having a water inlet, a water discharge pipe leading therefrom, an air pressure inlet, an air discharge outlet, valves for said inlet and outlet, a lever for operating the valves, and an open pan adapted to be sealed by the water in the cylinder and designed to receive the air pressure from the inlet, said pan being connected to and operating said lever.

In testimony whereof I affix my signature.

CHARLES I. CHAMBERS.
